VIBRATORY SCREENING DEVICE

James A. Flint, Bexley, Ohio, assignor to The
Taylor Vibrator Company, a corporation of
Colorado

Application December 12, 1934, Serial No. 757,159

5 Claims. (Cl. 209—311)

This invention relates to a vibratory screening device, particularly of the multiple screen type.

An object of the invention is to provide a screening device of the multiple screen type in which the screens are vibrated with respect to each other or provide what is herein termed a reaction screen.

Another object of the invention is to provide a screening device having a motor for vibrating a plurality of screens along an axis making an acute angle with a surface of each of the screens.

Still another object of the invention is to provide a new and improved mounting and tensioning means for a wire mesh screen.

Other objects of the invention will appear hereinafter, the novel features and combinations being set forth in the appended claims.

In the drawings:

Fig. 1 is a side elevational view of the device comprising my invention;

Fig. 2 is a sectional view of the device taken along the line 2—2 of Fig. 1 looking in the direction of the arrows;

Fig. 3 is a sectional view of the device taken along the line 3—3 of Fig. 2;

Fig. 4 is an enlarged sectional detail showing one wire mesh screen clamping means which may be employed; and

Fig. 5 is an enlarged sectional detail showing a modified form of wire mesh screen clamping means.

Referring particularly to Figs. 1, 2 and 3 of the drawings, there is illustrated a vibratory screening device which is herein designated as of the reaction type. This device comprises an upper vibratory screen assembly 10 and a lower vibratory screen assembly 11. The upper screen assembly 10 comprises a deck formed by a pair of laterally-disposed side plates 12 between which extend a plurality of lateral Z-shaped plates 13 which are rigidly attached at their opposite ends to said side plates 12, as by welding. Adjacent the bottom ends, both forwardly and rearwardly of the side plates 12, are provided the open end slots 14 and 15, respectively, for a purpose which will be hereinafter described.

Positioned adjacent said slots 14 and 15 is a pair of laterally-extending channel members 16 and 17, respectively, which are rigidly attached at their opposite ends to said side plates 12, as by welding. Extending longitudinally of the upper vibratory screen assembly 10 is a pair of reinforcing tubes 18 which pass through the Z-shaped plates 13 and are welded thereto. Said tubes 18

are also welded to the channel members 16 and 17 at their opposite ends.

Adjacent the top of each of the Z-shaped plates 13 is a cap member 19, preferably formed of rubber. The Z-shaped plates 13, together with the channel members 16 and 17, in cooperation with the reinforcing tubes 18 and the side plates 12, form a sill or deck across which is adapted to be stretched a wire mesh screen 20. The rubber cap members 19 provide a cushion between said screen 20 and the Z-shaped plates 13 to prevent undue wearing of said screen 20. The side edges of said screen 20 rest on flanges 20a extending inwardly from the side plates 12.

Extending longitudinally of said upper screen 15 assembly 10 is a pair of cylindrical pipes 21 and 22 adapted to be received, respectively, in the slots 14 and 15. Said slots 14 and 15 provide bearings for the ends of said pipes 21 and 22, which ends project laterally from the side plates 12, and rotatably maintain said pipes between said plates 12. Said pipes 21 and 22 are provided at each end with heads 23 and 24, respectively. Said heads 23 and 24 have central drill holes 25 and 26, respectively, adapted to receive inwardly-projecting pins carried by the brackets 27 and 28, respectively, which are rigidly attached to the ends of the plates 12, as by nuts and bolts 29 and 30, respectively. Said cylindrical pipes 21 and 22 have lever arms 31 and 32, respectively, rigidly attached thereto at each end, which have notched terminals 33 and 34, respectively, adapted to receive hooked bolts 35 and 36 yieldably held in retaining notches 37 and 38 of brackets 39 and 40 rigid with the side plates 12, through adjustable 35 spring bearing means 41 and 42. The wire mesh screen 20 is attached at one end to the pipe 21 by clamping means illustrated in detail in Figs. 4 and 5 hereinafter described and, at the other end, to the pipe 22 by similar attaching means. 40

It is manifest that the cylindrical pipes 21 and 22 are rotatably supported in the bearings of the plates 12 formed by the slots 14 and 15 and may be rotated therein by turning of the lever arms 31 and 32 under the control of tensioning means 41 and 42. By this construction, the screen 20 may be maintained under proper tension at all times. The open construction of the slots 14 and 15 also provides for ready removal of the pipes 21 and 22, for attaching a new screen thereto or placing a different mesh screen on the deck. 45

It is to be noted that the tops of the plates 13 do not lie in a single plane but, as viewed in section in Fig. 3, form the screen 20 to an arcuate configuration. This provides for the proper main- 50 55

taining of the screen 20 against the cap members 19 on said plates 13 when said screen is tensioned and prevents vibratory movement of said screen with respect to said cap members 19 during vibration of the unit.

Each of the side plates 12 is provided on its outer surface with a top angle member 43, a bottom angle member 44 and a plurality of transverse reinforcing bars or channel members 45, all of which are formed rigid with said plates 12, as by welding, and form reinforcing means for said plates 12.

Extending transversely between the side plates 12 and rigidly attached thereto at its ends, as by welding, is a channel member 46. The side plates of said channel member 46 are adapted to receive the head 47 of an armature shaft 48 of an electric motor or vibrator 49. Said head 47 is rigidly attached to the side plates of said channel member 46, as by nuts and bolts 50. Said head 47 is of hollow construction to reduce the weight thereof and is provided with a pair of central reinforcing webs 51. Cooperating apertures 52 and 53 are provided in said channel member 46 and head 47, respectively, to provide access to the interior of said hollow head 47.

The motor or vibrator 49 comprises an armature 54 of laminated iron rigidly secured to the armature shaft 48 by the bracket 55 rigidly attached thereto, as by nuts and bolts 56.

The field structure for said motor 49 constitutes a U-shaped core 57 built of laminations, the legs of which are surrounded by field windings 58. Said field windings 58 and the core 57 are rigidly mounted upon the brackets 59, which brackets are, in turn, adjustably mounted upon the U-shaped frames 60 by adjustable bolts 61 extending through the split base of said frames 60 and attached to the brackets 59 by spaced nuts 62. The bolts 61 may be adjusted with respect to the frames 60 by releasing the clamping bolts 63 and screwing said bolts 61 to any desired position. Said bolts 61 may thereafter be maintained in said position by screwing home the bolts 63. Thereafter spaced nuts 62 may be adjusted with respect to said bolts 61 to position variably the brackets 59 which, in turn, determine the position of the field structure of said motor 49 with respect to the armature 54. This adjustment provides one means to control variably the amplitude of vibration of the armature 54 with respect to the field of said motor 49.

The U-shaped frames 60 are provided with feet 64 which are adapted to be attached to the upwardly-projecting bosses 65 carried on the laterally-extending channel bars 66 by the screws 67 extending through drill holes in said feet 64 and threaded in apertures in said bosses 65. Rigidly attached between said channel bars 66, as by welding, is a pair of heavy cast rings 68. Said rings 68 are provided with upper and lower inwardly-projecting bosses 69 and 70, respectively. Rigidly clamped between said bosses 69 and 70 of said rings 68 is a plurality of stacked spring bars 71 preferably formed of spring steel and held in rigid clamping position to said rings 68 by clamping plates 72, which clamp the ends of said bars against the lower bosses 70 under the action of the studs 73. That is, by screwing down the studs 73, the plates 72 clamp the ends of the spring leaves 71 between said plates 72 and the bosses 70 of said rings 68.

The armature shaft 48 is provided with a lateral opening 173 through which said spring leaves 71 extend. Projecting inwardly of said opening

173 and adjacent the top thereof is a boss 14 forming a part of said armature shaft 48. Within said opening 173 and adjacent the bottom thereof is a clamping plate 75 which is adapted to be clamped against the spring leaves 71 and thereby clamp said spring leaves adjacent their centers between said clamping plate 75 and the boss 14 under the action of the threaded studs 76.

The clamping plate 75 may be provided with a bolt 77 threaded therein and extending through an opening in the web 78 of said armature shaft 48 around which extends a coil spring 79. Said bolts 77 and coil spring 79 are adapted to maintain the plates 75 within the opening 173 before the spring leaves 71 are clamped rigid in said opening, the coil spring 79 allowing free movement of said plate 78 under the action of the stud 76 in performing the clamping operation.

It is thus seen that the field structure of the motor 49 is rigidly attached to the ends of the spring leaves 71 while the armature of said motor is rigidly attached to the central portion of said spring leaves 71. It is therefore obvious that, if the field of said motor 49 is cyclically energized by a source of pulsating current, such as a source of commercial 60-cycle alternating current, there will be a periodic vibration of said armature with respect to said field structure and a consequent periodic deflection and restoration of the spring leaves 71. It may be stated that this period of vibration has a frequency which is twice the frequency of the energizing source; in the example mentioned it would be 120 cycles per second. This is due to the fact that each half-cycle of alternating current is effective to attract the armature toward the field of said motor 49 and to deflect thereby the spring leaves 71. When the force due to magnetic attraction decreases to zero, the energy stored in the spring leaves 71 is effective to move the armature of the motor 49 away from the field structure. It is manifest that with the usual commercial alternating current the deflecting forces will pass through zero twice during each cycle of operation.

Rigidly attached to the ends of the channel bars 66 is a pair of downwardly-projecting angle members 80 which extend laterally of the upper screen assembly 10 and are attached to the side plates 81 of the lower vibratory screen assembly 11 through plates 82; said angle members 80, plates 82 and side plates 81 being attached together, as by welding the plates 82 to the side plates 81 and by riveting or welding the plates 82 to the angle members 80. It is thus seen that said lower vibratory screen assembly 11 is rigidly attached to the field structure of the motor and vibrates as a unit therewith while the upper vibratory screen assembly 10 is rigidly attached to the armature structure of said motor and vibrates as a unit therewith.

The lower vibratory screen assembly 11 is of substantially the same construction as the upper vibratory screen assembly 10 except for the configuration of the side plates 81. Said lower vibratory screen assembly 11 comprises a deck formed by a pair of laterally-disposed side plates 81 between which extend a plurality of lateral Z-shaped plates 13 which are rigidly attached at their opposite ends to said side plates 81, as by welding. Adjacent the bottom ends, both forwardly and rearwardly of the side plates 81, are provided the open end slots 14' and 15', respectively, for a purpose which will be hereinafter described.

Positioned adjacent said slots 14' and 15' is a

pair of laterally-extending angle members 16' and 17', respectively, which are rigidly attached at their opposite ends to said side plates 81, as by welding. Extending longitudinally of the lower vibratory screen assembly 11 is a pair of reinforcing tubes 18' which pass through the Z-shaped plates 13' and are welded thereto. Said tubes 18' are welded to the channel members 16' and 17' at their opposite ends. Adjacent the tops of each of the Z-shaped plates 13' is a cap member 19' preferably formed of rubber. The Z-shaped plates 13', together with the channel members 16' and 17', in cooperation with the reinforcing tubes 18' and the side plates 81, form a sill or deck across which is adapted to be stretched a wire mesh screen 20'. The rubber cap members 19' provide a cushion between said screen 20' and the Z-shaped plates 13' to prevent undue wearing of said screen 20'. The side edges of said screen rest on flanges 20b extending inwardly from the side plates 12'.

Extending longitudinally of said lower screen assembly 11 is a pair of cylindrical pipes 21' and 22' adapted to be received, respectively, in the slots 14' and 15'. Said slots 14' and 15' provide bearings for the ends of said pipes 21' and 22' which ends project laterally from the side plates 81 and rotatably maintain said pipes between said plates 81. Said pipes 21' and 22' are provided at each end with heads 23' and 24', respectively. Said heads 23' and 24' are provided with central drill holes 25' and 26', respectively, adapted to receive inwardly-projecting pins carried by the brackets 27' and 28', respectively, which are rigidly attached to the ends of the plate 81, as by nuts and bolts 29' and 30', respectively. Said cylindrical pipes 21' and 22' have rigidly attached thereto at each end brackets 31' and 32', respectively, which have notched terminals 33' and 34' adapted to receive hooked bolts 35' and 36' yieldably held in retaining notches 37' and 38' of brackets 39' and 40' rigid with the side plates 81 through adjustable spring bearing means 41' and 42'. The wire mesh screen 20' is attached at one end to the pipe 21' by clamping means illustrated in detail in Figs. 4 and 5 hereinafter described, and, at the other end, to the pipe 22' by similar attaching means.

It is manifest that the cylindrical pipes 21' and 22' are rotatably supported in the bearings of the plates 81 formed by the slots 14' and 15' and may be rotated therein by turning of the brackets 31' and 32' under the control of tensioning means 41' and 42'. It is thus manifest that the screen 20' may be maintained under proper tension at all times. The open construction of the slots 14' and 15' also provide for ready removal of the pipes 21' and 22'. It is to be noted that the tops of the plates 13' do not lie in a single plane, but as viewed in section in Fig. 3, form the screen 20' to an arcuate configuration. This provides for the proper maintaining of the screen 20' against the cap members 19' on said plates 13' when said screen is tensioned and prevents vibratory movement of said screen with respect to said cap members 19' during vibration of the unit 11.

Each of the side plates 81 is provided on its outer surface with a top angle member 43', a bottom angle member 44' and a plurality of transverse reinforcing bars or channel members 45', all of which are formed rigid with said plates 81, as by welding, and form reinforcing means for said plates 81.

Said lower screen assembly 11 is also provided adjacent the side walls 81 with a pair of in-

clined inwardly-extending plates 191 which form flanges against which the sides of the screen 20' are adapted to rest. It may be noted that said lower screen assembly 11, including said screen 20', is somewhat wider than the upper screen assembly 10. Said screen 20' therefore effectively receives any material which may pass through said upper screen 20.

Rigidly attached to the side plates 81 adjacent the upper portion of the lower screen assembly 11 is a plurality of brackets 82' adapted to carry spring leaves 83 each of which is clamped to one of said brackets 82' adjacent one end thereof as by the clamping plates 84 and the screws 85. The other end of each of said spring leaves 83 is attached by clamping plates 86 and screws 87 to one of the brackets 88 rigidly attached to the bottom portion of the side plates 12 of the upper screen assembly 10.

The side plates 81 of the lower screen assembly 11 are provided at one end thereof with supporting eyes 89, said eyes being preferably carried in the top flange of the angle member 43' of said side plates 81. Flexible mounting means for supporting the device is attached to said eyes 89 and comprises a hooked bolt 90 around which is coiled a coil spring 91, one end of which rests against a washer under the nut 92 on said bolt 90 and the other end of which rests against the bottom of a cylinder 93, the upper end of which cylinder is attached to a suspension rod 94.

The upper channel bar 66 also carries laterally spaced plates 95 provided with holes 96 adapted to receive selectively the bolt of a clevis 97 which clevis is attached by a chain link 98 to the hook 35 end of a spring mounting means 99 similar to that cooperating with the eyes 89. A turnbuckle 100 is interconnected with the spring mounting means 99 and a suspension rod 101. There will, of course, be a pair of suspension rods 101 and 40 94, each of which is adjacent a side of the device whereby said device may be supported.

It is to be particularly noted that, as viewed in Figs. 1 and 3, the longitudinal axis of the motor 49—that is, the axis of vibration of said motor—is disposed at an angle with respect to the surface of the screen 20 of the upper vibratory assembly 10 and the corresponding assembly of the lower vibratory assembly 11. By virtue of this construction, said motor 49 in its vibration not only imparts a vibratory movement to the screen 20 which is effective to lift periodically any material on said screens therefrom but is also effective to impart a conveying action to said particles of material. Where the screens are set at an inclination to the horizontal, there will, of course, be a natural gravity feed operating on any material on said screens which will tend to move the material from the upper to the lower portion thereof as said screens are vibrated. This movement of particles across the screens may be augmented by the conveyor action of the vibratory motor 49 when said motor is inclined as illustrated in Figs. 1 and 3. If desired, the axis of said motor 49 may be made substantially perpendicular to the average surface of the screens under which condition no appreciable conveyor action would be imparted by said motor 49, gravity alone then providing any conveyor action. If desired, the axis of said motor 49 may be inclined 65 to the planes of said screens at an acute angle opposed to the acute angle thereof illustrated in Figs. 1 and 3. Under these conditions, with the screens mounted at an angle as illustrated in Figs. 1 and 3, the conveyor action of the vibratory

70 75 80 85 90 95 100

motor 49 would be opposed to the gravitational conveyor action on said particles. This result may also be accomplished by merely raising the lower end of said screens, as viewed in Figs. 1 and 5, so that said end, which is now illustrated as the lower end, becomes the higher end; that is, the screens are tilted in an opposite direction. Under these conditions, the material to be screened would, of course, be fed at the higher 10 end, as it quite usually is, and the conveyor action of the motor 49 would be opposite a gravitational conveyor action on said material. If desired, the screens may be placed substantially horizontal in which case the conveyor action of the material being screened will be due almost entirely to that of the motor 49.

As a typical illustration of how the device of my invention may be employed, it may be stated that with said device supported, as illustrated in 20 Figs. 1 and 2, material to be screened may be fed at the upper end of the upper screen assembly 10. Said upper screen is generally appreciably coarser than the lower screen. For example, said upper screen may be a 10-mesh screen and the lower 25 screen may be a 20-mesh screen. As the material to be screened passes downwardly across said upper screen under the vibratory movement thereof and under the combined conveyor action due to gravity and due to the motor 49, those 30 particles which will pass the 10-mesh screen pass therethrough and fall onto the lower screen. Material which is incapable of passing the 10-mesh screen will be discharged at the lower end of the upper screen assembly 10 as, for example, into a hopper or receptacle. The material which passes through said upper screen and is received on said lower screen is subjected to another screening operation and the constituent parts thereof which will pass through the lower screen, in the example given a 20-mesh screen, pass through said lower screen and into a hopper or a receptacle placed beneath it. The fractions thereof which have passed the upper screen but are too large to pass lower screen will be discharged at the end of said lower screen into some kind of a receptacle or hopper.

Referring particularly to Fig. 4, there is illustrated in sectional detail the particular construction of one means which may be employed to clamp the screen 20 or 20' to the end cylinder 22 or 22'. This means is duplicated for each screen and for each end of the device and thus a description of one will suffice. A pair of angle members 102 and 103 is clamped together by bolts and nuts 104 and clamp therebetween said screen 20. The lower of said angle members is extended at one side at 105 and is provided along its length with a plurality of apertures 106. Throughout the length of the pipe 22 extend a plurality of rods 107, one end of which is welded to the pipe 22 and the other end of which projects outwardly therefrom and is preferably hooked as at 108. There is a rod 107 for each of the apertures 106 of the lower angle member 103. Said apertures 106 are adapted to be removably held to said pipe 22 by virtue of the hook portion 108 of said rods 107. It is thus manifest that by rotating the pipe 22, the screen 20 will be wrapped about the surface thereof and tensioned. Adjacent the top of the channel member 11 is provided an angle bearing block 109 preferably formed of wood which is adapted to prevent contact between said screen 20 and said channel 11. The screen and clamping device of Fig. 4 is preferably employed for heavy or coarse screens.

In Fig. 5, there is illustrated a slight modification of the screen clamping device illustrated in Fig. 4 which is particularly adapted to be used with fine mesh screens. This device differs from that of Fig. 4 in that the means for clamping the end of the screen 20 comprises a lower plate 110 and an upper channel member 111 adapted to carry a clamping block 112, preferably formed of maple. Said clamping members 110, 111 and 112 are clamped together by a plurality of longitudinally-extending nuts and bolts 113. The lower clamping plate 110 is provided with a plurality of longitudinally-extending apertures 114 adapted to cooperate with the hooked ends of the rods 107. This construction is preferred for 15 the fine screen because said screen is not bent at a sharp angle which might tend to break the strands thereof.

As was previously pointed out, the channel members 66 were rigidly attached to the field 20 structure of the motor 49 and the armature shaft 48 was rigidly attached to the armature thereof and upon energization of said motor 49, there was relative movement between said armature shaft 48 and said angle members 66. It 25 is manifest from the above description that the upper vibratory screen assembly 10 is rigidly attached to the armature shaft 48 through the channel member 46 and the side plates 12 of said upper screen assembly 10 and that the lower vibratory screen assembly 11 is rigidly attached to said channel members 66 by means of the depending angle members 80 and the side walls 81 of the lower screen assembly 11. In addition, the upper vibratory assembly 10 and the lower 30 vibratory assembly 11 are flexibly attached by the spring leaves 83. It is thus manifest that when said motor 49 is energized, there will be a relative vibratory movement between the upper vibratory assembly 10 and the lower vibratory 35 assembly 11. The period of this vibration will be determined by the frequency of the source which energizes the motor 49 and will be twice this frequency.

The amplitude of vibration of the upper vibratory assembly with respect to the lower vibratory assembly will, of course, be determined by the amplitude of vibration of said motor 49. This may be controlled by the adjustable means of said motor above described and may additionally be controlled by varying the amount of current flowing in the field winding of said motor as, for example, by controlling a variable resistor which may be inserted in the line of the field winding of said motor.

The distribution of the energy between the upper vibratory assembly and the lower vibratory assembly and the consequent absolute vibration of each of these assemblies—that is, the vibration of each assembly with respect to space—may be proportioned as desired. This is effected by controlling the relative weights of each of the vibratory assemblies and all parts which are rigidly attached thereto and vibrate as a unit therewith. For example, if the upper vibratory assembly and all the parts rigid therewith has a weight which is equal to that of the lower vibratory assembly and all the parts rigid therewith, each of the screen assemblies will have the same amplitude of vibration and the energy of said motor 49 will be equally divided between them. By making the weight of one of the vibratory assemblies greater than that of the other, it will have a smaller amplitude of vibration. That is, the absolute amplitude of vi-

bration of each of the screen assemblies in inversely proportional to the weight of said assembly and the parts rigid therewith.

For most materials encountered in actual practice, it is desirable to provide greater amplitude of vibration for the upper screen assembly 10 than for the lower screen assembly 11. This is due to the fact that the raw material to be screened is first received on the upper screen 20 and thus there is a very large range of sizes of material on the upper screen. For example, the size ranges of the material may vary from zero to the maximum size of material received. This screen therefore has a difficult operation to perform. The lower screen assembly need only operate on those sizes of materials which will pass the upper screen; thus its operation is less severe. For this reason, it is usual to design the relative weights of the upper and lower vibratory assemblies so that the upper vibratory assembly will have the greater amplitude of vibration. It has been found that by giving the upper vibratory assembly approximately 40 per cent of the total weight and the lower vibratory assembly approximately 60 per cent thereof, a ratio will result which is satisfactory for most purposes. This ratio is, of course, not at all critical and may be varied as desired. Under certain conditions, as for example, where the material to be treated is very largely of a size range which will pass the first screen without much vibration, it may be desired to distribute the weight so the lower vibratory assembly will have the lesser weight and thus the greater amplitude of vibration. A typical example of where the upper vibratory assembly 10 should have the greater weight and thus lesser amplitude of vibration is when the same size screens as above mentioned are employed and finished cement which has only a relatively few large impurities, such as broken machine parts, unground clinkers, etc. is being treated.

While it is not necessary to the operation of my device, it greatly increases the efficiency of operation thereof and substantially reduces the amount of energy required to vibrate the screens, to proportion the weights of the vibratory structures so that, as a unit, they are effective under the action of the spring leaves 71 to have a natural period of vibration which is approximately the same as the frequency of vibration of the motor 49.

Exact resonance is not necessary or even desirable and it is preferred that the natural period of said vibratory structures be slightly higher than the period of vibration of said motor 49. This means that there will always be some load on said motor 49 which provides improved control of the amplitude of vibration of the device and prevents any tendency of the device to destroy itself when doing no useful work. In addition, this allows some adjustment of the period of vibration of the vibratory structures to bring them nearer the resonance with the period of said motor by the simple expedient of slightly relieving the clamping compression on the spring leaves 71.

It is, of course, obvious that the natural period of vibration of the mentioned vibratory structures

is not determined solely by their weights or their relative weights but is also determined very appreciably by the restoring force which the spring leaves 71 exert when deflected. This, of course, is determined by the texture of said spring leaves, their cross-sectional area, their length and the mounting of said springs, and is also affected to some extent by the rigidness of the clamping means adjacent the ends thereof.

Attention is directed to the fact that the spring leaves 83 are disposed at an angle which form substantially a right angle with the longitudinal axis of the motor 49. This condition should be maintained for any position of said motor 49 whereby the axis of vibration of said upper and lower screen assemblies 10 and 11 is substantially at right angle to the plane of said spring leaves 83. It is also to be noted that at least part of the reinforcing bars or channels 45 and 45' is parallel with the axis of vibration of motor 49.

While the motor 49 may be set at any desired angle with respect to the screens 20 and 20', where a conveyor action is desired, it has been found that this angle is preferably between 45 and 80 degrees with said screen surfaces 20 and 20' when this conveyor action is desired.

While the screen surfaces 20 and 20' are preferably substantially parallel as illustrated in the drawings, this construction is not absolutely essential and, if desired, they may be inclined at an acute angle with respect to each other. For example, the lower screen 20' might be mounted substantially horizontal while the upper screen 20 is inclined at an angle horizontal with the axis of the vibratory motor 49 either perpendicular to one of said screens or inclined to each of them. This construction will, of course, provide a different conveyor action of the motor 49 with respect to said screens 20 and 20' as the conveyor action of the motor with respect to each screen is determined by the angle the axis thereof makes with said screen.

Obviously those skilled in the art may make various changes in the details and arrangement of parts without departing from the spirit and scope of the invention as defined by the claims hereto appended, and I wish therefore not to be restricted to the precise construction herein disclosed.

Having thus described and shown an embodiment of my invention, what I desire to secure by Letters Patent of the United States is:

1. In a vibratory screening device, the combination with a plurality of superimposed screens of different mesh carried by vibratory structures of different masses, of a vibratory electric motor for vibrating said vibratory structures and having an armature attached to vibrate with one of said structures and a field attached to vibrate with the other of said structures, and flexible means supporting said screens and providing for movement of both which has a predominant vertical component.

2. In a screening device, the combination with a pair of superposed screen decks, of means attaching said decks together for relative vibratory movement comprising members on opposite sides of one of said decks, a heavy flat vibrator spring extending between and attached at its ends to said members, means attaching the center of said vibrator spring to said other deck, an electromagnetic vibratory motor having an armature rigidly attached to one of said decks and a field structure attached to the other of said decks and operable at a predetermined frequency bearing 75

a fixed relation to the frequency of the operating alternating current, and means suspending said screens to provide for their vibratory movement with a substantial vertical component.

- 5 3. In a vibratory screening device, the combination with a pair of superposed screens of different mesh, of flexible means connecting said screens for relative movement, flexible means for supporting said screens to provide a horizontal component of movement of both of them, a vibratory electric motor constructed and arranged to vibrate at a fixed frequency predetermined by the frequency of the available commercial alternating current, said motor comprising a field structure attached to one screen and an armature attached to the other, and a strong deflectable spring connected between said field structure and said armature.
- 10 15 4. In a vibratory screening device, the combination with a pair of superposed screens of different mesh, of flexible means connecting said screens for relative movement, flexible means for supporting said screens to provide a horizontal component of movement of both of them, a vibratory electric motor constructed and arranged to vibrate at a fixed frequency predetermined by the frequency of the available commercial alternating current, said motor comprising a field structure attached to one screen and an armature attached to the other, and a strong deflectable spring connected between said field structure and said armature.
- 20 25 5. In a vibratory screening device, the combination with a plurality of screens, of a straight line vibration type, of vibratory motor having an armature attached to one screen and a field structure attached to the other, said motor being operable to impart straight line motion to said screens having a vertical component, and means for flexibly supporting said screens to provide for the aforementioned straight line motion of them.

different mesh, of flexible means connecting said screens for relative movement, flexible means for supporting said screens to provide a horizontal component of movement of both of them, a vibratory electric motor constructed and arranged to vibrate at a fixed frequency predetermined by the frequency of the available commercial alternating current, said motor comprising a field structure attached to one screen and an armature attached to the other, and a strong deflectable spring connected between said field structure and said armature.

5. In a vibratory screening device, the combination with a plurality of screens, of a straight line vibration type, of vibratory motor having an armature attached to one screen and a field structure attached to the other, said motor being operable to impart straight line motion to said screens having a vertical component, and means for flexibly supporting said screens to provide for the aforementioned straight line motion of them.
